CALF PULLER

Worth L. Matteson, Jr., Foreman, Ark.

Application September 28, 1951, Serial No. 248,820

1 Claim. (Cl. 128—352)

1

This invention relates to animal husbandry, and more particularly to devices for assisting delivery of calves.

A main object of the invention is to provide a novel and improved calving device which is simple in construction, which is easy to operate, and with which pressure may be applied to a cow during pulling of its calf in a novel manner such that delivery of the calf is facilitated.

A further object of the invention is to provide an improved calving device which involves inexpensive components, which is sturdy in construction, which is easy to set up, and which provides pressure to the rump of the cow in a manner facilitating delivery of the calf and reducing the time required to extract the calf from the cow.

Further objects and advantages of the invention will become apparent from the following description and claim, and from the accompanying drawings, wherein—

Figure 1 is a side elevational view showing the manner in which the improved device of the present invention is applied to a cow to assist calving.

Figure 2 is a vertical longitudinal cross sectional view taken through the improved device employed in Figure 1.

Figure 3 is a top plan view of the calving device of Figures 1 and 2.

Figure 4 is an enlarged fragmentary cross sectional view showing the detachable joints between the rod sections transmitting thrust to the rump portion of the cow whereby pulling force may be developed for extracting the calf therefrom.

Figure 5 is a fragmentary enlarged side elevational view showing the operating lever and the ratchet wheel employed in the improved calf pulling device of the present invention.

Referring to the drawings, the improved obstetrical device is designated generally at 11 and comprises a U-shaped breeching bar 12 adapted to be placed against the rump 13 of a cow, as shown in Figure 1, with the side arms 14, 14 of the breeching bar extending forwardly around the haunches of the cow. Secured to the respective ends of the side arms 14, 14 are the flexible strap sections 15 and 16 adapted to extend over the back of the cow and to be secured together at the buckle 17 in the manner shown clearly in Figure 1. Rigidly secured to the intermediate portion of the breeching bar 12 is the rearwardly and axially extending cup member 18 which receives one end of a first rigid tubular

2

rod 19. Designated at 20 is a second rigid tubular rod having a shaft element 21 secured in one end portion thereof, as by a transverse rivet 22, the shaft element 21 being adapted to telescopically engage in the end of the first rigid rod member 19, as shown in Figure 4. The other ends of the second rod 20 is provided with a gripping handle 23 of rubber or similar flexible material. The rods 19 and 20 together with the cup member 18 and handle 23 form an elongated support.

Rigidly secured to the elongated support adjacent the other end thereof or rear portion of the rod 20 adjacent the handle 23 is an upper standing, substantially triangular lug 24. Pivotally connected to the lug 24, at 25, are the respective parallel link bars 26, 26, and pivotally connected between the ends of the link bars 26, 26 by a transverse rivet 27 is an arm 28. A yoke member 29 is disposed longitudinally above the elongated support between the lug 24 and the one end of the support which is secured to the cup member 18 and has one end pivotally connected to the lug 24. Specifically, the yoke member 29 comprises the opposing, outwardly bowed bar members 30, 30 rigidly secured at their rear ends, as viewed in Figure 3, to the end of the arm 28. The forward ends of the bars 30, 30 are connected together and have secured thereto the upstanding eye member 31.

A reel 33 is mounted on the yoke member 28 for rotary movement about an axis disposed transversely of the elongated support. Specifically, the axis is the rivet 32 which extends transversely through the mid-portions of the opposing bars 30, 30, of the yoke member 29 and journaled on the rivets is the reel 33, the reel having the ratchet wheel 34 rigidly secured to one side thereof. Wound on reel 33 is a cable 35 which extends through the eye member 31 and is fastened to a hook 36 which in turn is secured to the obstetrical chain 37. Designated at 38 is a lever having the spaced arms 39, 39 rigidly secured thereto, at its lower portion, said arms straddling the reel 33 and being pivotally connected to the transverse rivet 32. Designated at 40 is a dog pivoted at 41 to the lever 38 between the arms 39, 39 and arranged to engage ratchet wheel 34, as is clearly shown in Figure 5. The dog 40 is formed with the upwardly extending release arm 42 which extends clear of the lever 38 so that the engaging end of the dog 40 may be moved away from engagement with the teeth of the ratchet wheel 34 responsive to clockwise rotation of the dog 40, as viewed in

Figure 5. As shown in Figure 5, the upper end of the dog 40 is provided with the finger-engaging portion 43 which may be depressed by the operator's thumb to release the ratchet wheel 34. Pivoted to the yoke 29 forwardly of the ratchet wheel 34, as by a transverse rivet 44 is a latch dog 45 which is biased by a suitable spring, not shown, into locking engagement with the periphery of ratchet wheel 34 and which normally prevents said ratchet wheel from rotating in a counterclockwise direction, as viewed in Figure 5. The locking dog 45 may be swung out of engagement with respect to the periphery of ratchet wheel 34 by rotating said dog in a clockwise direction, as viewed in Figure 5.

In using the device, the device is assembled in the manner shown in Figures 1 to 3, the forward end of rod 19 being engaged in the socket member 18 and the breech bar 12 being disposed on the rear portion of the cow, in the manner shown in Figure 1 and being supported by the connected strap members 15 and 16. The second rod member 20 is engaged with the end of the first rod member 19 by inserting the shaft element 21 into the rear end of rod member 19. The obstetrical chain 37 is fastened to a portion of the calf's body, as for example, to the calf's legs and the cable 35 is connected to the obstetrical chain 37 by means of the hook member 36. Tension may then be applied to the cable 35 by rotating lever 38 clockwise, as viewed in Figure 2, the device being supported by grasping the handle 23 with one hand while rotating the lever 38 with the other hand. It will be noted that the torque is applied to reel 33 through the engagement of dog 40 with ratchet wheel 34 and that the lever 38 may be rotated through a substantial angle in a clockwise direction, as viewed in Figure 2, to apply tension to the cable 35. After each step of rotation, the lever 38 may be returned to its starting position, as for example, the position thereof shown in Figure 2, the ratchet wheel 34 being meanwhile held locked by the engagement of the dog 45 therewith. It is therefore possible to apply successive pulling forces to the cable 35 in a rapid and convenient manner, whereby the extraction of a calf may be rapidly accomplished

without the necessity of unduly restraining the cow during the process. It will be further noted that the application of the reactive thrusts developed in the rod members 20 and 19 to the rump portion of a cow through the breech bar 12 tends to cause arching of the cow's back, facilitating delivery of the calf.

While a specific embodiment of an improved calf pulling device has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A calf puller comprising an elongated support, a U-shaped breeching bar disposed transversely of said support and secured to one end thereof and adapted to transversely embrace and be secured to the rump of a cow, an upstanding lug secured to said support adjacent the other end thereof, a yoke member disposed longitudinally above said support between said lug and said one end of said support and having one end pivotally connected to said lug, a reel mounted in said yoke member for rotary movement about an axis disposed transversely of said support, a cable wound upon said reel and having one end secured thereto an obstetrical chain carried by the other end of said cable, and a hand actuated paying-out and reeling-in means operatively connected to said reel for effecting the rotary movement thereof.
